2 SHEETS—SHEET 2.

James M. Cammack.
Inventor,

By his Attorney, James P. Duhamel,

UNITED STATES PATENT OFFICE.

JAMES M. CAMMACK, OF BROOKLYN, NEW YORK.

RADIATOR.

1,350,066.

Specification of Letters Patent. Patented Aug. 17, 1920.

Application filed April 22, 1916, Serial No. 92,889. Renewed January 13, 1920. Serial No. 351,255.

To all whom it may concern:

Be it known that I, JAMES M. CAMMACK, a citizen of the United States, and resident of Brooklyn, in the county of Kings and State of New York, have invented certain new and useful Improvements in Radiators, of which the following is a specification.

This invention relates to steam radiators and more especially to gas fired multiple section radiators comprising a burner beneath the sections and sectional housings inclosing the burner and suspended from and beneath the same so they can be removed separately for cleaning, and removable end plates 10 for a means of access to clean the interior of the housings without removing the latter, the whole to be carried by the end sections; together with a filling cup which limits the amount of water that can be poured into the 15 radiator for conversion to steam, as will be more fully described in the following specification, set forth in the claims and illustrated in the accompanying drawings, wherein;

25 Figure 1 is a side view of the improved radiator.

Fig. 2 is an end view of the same.

Fig. 3 is a view of the other end with the supply pipes.

30 Fig. 4 is a vertical sectional view through the front end of the radiator.

Fig. 5 is a plan view of one of the housing sections.

Fig. 6 is an elevation of the same.

35 Fig. 7 is a sectional view of the filling cup.

Fig. 8 is a side view of the same.

In the construction of gas fired radiators where extensions are made to the radiator 40 sections to protect the flame, it is often necessary to gain access to the burner or to remove one or more sections separately to clean within the housing, and in the present invention the removal of a section of the housing 45 is dispensed with by providing end plates which may be removed to clean the burner or make repairs without disturbing the balance of the heater.

The radiator sections 10 are of the usual 50 type and one of the end or leg sections has a blow-off 11 to guard against abnormal steam pressure and consequent damage which might result therefrom.

By referring to Figs. 7 and 8 the filling 55 cup will be seen on a larger scale and that the threaded part 13 of the cup is horizontal

while the inlet end is inclined upward and is closed by a plug 15 screwed therein when the water is being heated. The lower edge 16 of the inlet is slightly below the upper side 17 60 of the end 13 so that when the water is introduced into the radiators, they may be filled only so high as the edge 16 and the air always finds an outlet along the upper inner side of the cup.

65 When filling the radiator the overflow of water always indicates that the limit of the water line has been reached and that no more is necessary. The plug 15 having means on its outer side for turning the same, is then 70 inserted and the generation of steam is then proceeded with.

The gas for the heating of the water is introduced through suitable piping connected with the nipple 18 on the regulator 75 19 and through the pipe 20 and mixer 21 it enters the burner 22 and escapes through the tips 23.

An undesirable feature in gas regulators is the liability of the flame to blow out and the 80 consequent endangering of the lives of the occupants of the apartments in which the heater is located, and the danger of clothing and other articles catching fire from the unprotected flames and to overcome these objections 85 housings 24 are hung from the ends of the sections 10 to protect the flames from the burner 22 and to confine the heat therein. These housing sections are provided for each radiator section and from the outside appear to be a continuation of the section. 90

These housing sections are supported by cross pieces 25 connecting the legs 25 at the lower ends of the end radiator sections. 95 In the drawings it will be seen that the housings 24 are similar in shape to the sections 10 and fit beneath the couplings 28 of the said section and for that reason the top edges 29 of the abutting flanges 30 are 100 beveled.

The leg sections of the radiator are complete and without housing sections but have vertical sides to coöperate with the flanges of the next housings and are supported on the legs 25; each leg or end section has an outer opening adapted to be covered by plates 26 and 27 screwed to the edges of the openings and removable to clean the inside or to make repairs. The 110 plate 26 has an opening for the gas pipe and a perforation 31 for lighting the burner

and the housing sections also have perforations 32 for the entrance of air to supply the burner.

When the radiator sections are assembled 5 the supporting bar 24' is put in place and the housing sections may then be secured to the under side of the bar and on the lower ends of the radiator sections, screws 33 passing through the housings and into 10 the bar to support the former making it possible to separately remove the housings if desired.

It is obvious that the parts may be otherwise arranged or modified without departing 15 from the essential features shown and described, or from the scope of the appended claims.

What I claim is:

1. In a gas fired radiator, the combination 20 of radiator sections coupled together, of leg sections at each end of the radiator and having openings and cross pieces, a bar supported by the cross pieces, removable

plates covering the openings, a burner carried by the bar, and separate perforated 25 housing sections beneath the radiator sections and hung from the bar.

2. In gas fired radiators, the combination with end sections having openings, of legs 30 for the end sections, couplings for the sections, a filling cup for one of the leg sections on a level with the coupling and having its lower inlet edge at the water line of the radiator and its upper inner edge above said water line, a burner carried by 35 a bar connecting the leg sections, intermediate sections above the burner, and housings about the burner and supported by the connecting bar.

Signed at New York, in the county of 40 New York and State of New York, this 6th day of April, A. D. 1916.

JAMES M. CAMMACK.

Witnesses:

JAMES F. DUHAMEL,

Wm. C. WOLF.
